UNITED STATES PATENT OFFICE.

CLARENCE E. BARNES, OF WARREN, OHIO.

GAS GOVERNOR.

1,406,817.

Specification of Letters Patent. Patented Feb. 14, 1922.

Application filed May 15, 1920. Serial No. 381,640.

To all whom it may concern:

Be it known that I, CLARENCE E. BARNES, a citizen of the United States, residing at Warren, in the county of Trumbull and State of Ohio, have invented certain new and useful Improvements in Gas Governors; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to melting pots for type casting machines, and the like, and the object of the invention is to provide a novel construction of means for automatically controlling the supply of liquid, or gaseous, fuel to the burner, or burners, beneath the pot, according to the temperature of the molten metal therewithin.

With this object in view, and others appearing as the specification proceeds and the nature of the invention is more fully disclosed, the invention resides in the novel construction, combination and arrangement of parts, as will be hereinafter fully described, summed up in the claims, and illustrated in the drawing.

The accompanying drawing clearly illustrates an exemplary form of embodiment, capable of carrying out the underlying principles of the invention. Briefly described:

Figure 1 is a fragmentary sectional view of a melting pot such as is used, for instance, in type casting machines, equipped with my improvements;

Figure 2 is a fragmentary detail view, partly in elevation and partly in section, of the upper portion of the device, constituting my invention, and showing more particularly the valve and the means for supplying the thermostatic element to the stand-pipe; and,

Figure 3 is a fragmentary sectional view in side elevation of the means for adjusting the position of the valve.

Referring now in detail to the drawing:

1 designates a receptacle, such as a melting pot, used in type casting machines and adapted to contain molten material, such as metal.

Disposed vertically within said melting pot 1 is a tube 2, preferably of relatively

thin metal, constituting a conductor of heat. Said tube is closed at its lower end in a suitable manner, as by means of a removable plug 3, which may be threaded into said lower end of the tube. As shown, said tube is adapted to be supported with its bottom in proximity to the bottom of the receptacle 1, and at its upper end is connected in any suitable manner, as by means of threaded engagement, with a pipe 4, preferably having an elbow 5 intermediate its length, and the portion 6 of said pipe projecting vertically above the receptacle 1 is threaded at its free end for engagement with the internally threaded end of a valve casing 7. As shown, said valve casing is hollow and the pipe 6 communicates with the hollow chamber thereof. Said valve casing is provided with an upper lateral flange 8, adapted, as shown at 9, for engagement with the threaded end of an inlet pipe 10, leading from a suitable source of fuel supply, either liquid or gaseous.

Suitably secured to the flange 8, as by means of bolts 11 carrying nuts 12 on the threaded ends thereof, is a cover 13, provided with a dished portion 14 and with a hollow nipple 15 for engagement with the threaded end of an outlet pipe 16, leading to the burner, or burners, beneath the melting pot 1.

The valve casing 7 is provided with an inlet port 17, normally closed by a threaded plug 18. By removing the plug 18 a suitable expandible thermostatic medium, such as mercury, 19 may be filled into the pipe 6 and into the tube 2 until the level of such mercury is slightly below the flange 8 of the valve casing 7.

Within said valve casing 7 are disposed valves 19', preferably steel balls, one, or a number of which, may be used as desired, and, as herein shown, three of such balls are given as an example. Said balls are superposed within the valve casing 7 and float upon the body of mercury within the pipe 6 and tube 2.

The valve casing 7 is provided with a second nipple 20 for the reception of a screw 105 21 of a diameter approximating the diameter of the bore of said nipple. The bore of said nipple is enlarged at the outer end thereof to provide a recess for the reception of a packing or gasket 22 and the free end 110 of said nipple is closed by a screw cap 23, through which said screw 21 is threaded, as

shown. By moving said threaded member in and out of the nipple 20, the mercury therewithin is displaced, so as to raise or lower the valves 19' and thus bring the top 5 valve nearer to or farther away from the bottom of the opening through the nipple 15, thus contracting or enlarging the passage of the fuel to said pipe 16.

In operation, the device is adjusted so that 10 the mercury will not act to close the valves 19' until the temperature of the molten metal within the melting pot 1 exceeds approximately 550° F., which is the right temperature for casting perfect slugs or lines of 15 type. As the metal is withdrawn from the pot, the remaining metal therewithin becomes increasingly hotter, so that the mercury expands and causes the steel balls, or valves 19' to rise, thus progressively decreasing the space for the passage of the fuel through said pipe 16, as the temperature within the pot increases, thus decreasing the feed of the fuel and thereby keeping the molten metal at the desired temperature. 20 25 My device embodies no springs which are likely to weaken, and no rubber which has a tendency to rot, and by means of the steel balls, the mercury is kept far enough from the gas feed and outlet so that there is no

chance of the mercury being blown out into 30 the gas pipes by the pressure of the gas.

What I claim to be new is:

1. The combination with a melting pot for metals of a casing providing a chamber having an inlet and outlet port, a tube closed 35 at the lower end extending downwardly into the pot and having its upper end opening into the casing, a thermal responsive liquid in the tube and casing and stopping short of the chamber, and a plurality of super- 40 posed balls within the casing floated upon the liquid, the upper being adapted to approach the outlet port and vary the overflow.

2. The combination with a melting pot 45 for metals of a casing providing a chamber having an inlet and an outlet port, a tube closed at its lower end extending downwardly into the pot and having its upper end opening into the casing, a thermal responsive liquid in the tube and casing stopping short of the chamber, a ball adapted to approach the outlet port and vary the overflow, and means within the casing floating upon the liquid and supporting the ball. 50 55

In testimony whereof I hereunto affix my signature.

CLARENCE E. BARNES.
